UNITED STATES PATENT OFFICE.

SUEL J. SPAULDING, OF DES MOINES, IOWA.

DESIGN FOR A DISPLAY-FRAME FOR PASTEBOARD BOXES.

SPECIFICATION forming part of Design No. 35,122, dated September 17, 1901.

Application filed July 19, 1901. Serial No. 68,982. Term of patent 7 years.

To all whom it may concern:

Be it known that I, SUEL J. SPAULDING, a citizen of the United States, residing at Des Moines, in the county of Polk and State of Iowa, have invented and produced a new and original Design for Display-Frames for Pasteboard Boxes, of which the following is a specification.

Reference being had to the accompanying drawings, forming part thereof, Figure 1 shows a top or plan view of the complete frame. Fig. 2 shows a transverse sectional view through the indicated line 2 2 of Fig. 1, and Fig. 3 shows a like view through the indicated line 3 3 of Fig. 1.

As shown in the drawings, the leading or material features of my design comprise a frame having its outer contour approximately in the form of a parallelogram, one corner of which at 10 is extended parallel with one of the axes of the frame, taken from one corner to the diametrically opposite corner. At the bottom of the frame is a flat base 11. A rim 12 projects at right angles to the base and surrounds the entire frame. Projecting inwardly

from the corner 10 is a triangular block 13, the sides of which are at right angles to the base 11 and its top flush with the top of the frame 12. In the corner diametrically opposite from the corner 10 is a block 14, extending toward the center of the frame and having two surfaces at 15 parallel with the rim opposite them, and at the central portion of this block are two surfaces 16, parallel with and of the same length as the inner edges of 35 the block 13. The top of this block 14 is flush with the top of the rim 12.

Having thus described my invention, what I claim as new, and desire to secure by Letters Patent of the United States, is—

The design for a display-frame for pasteboard boxes, substantially as herein shown and described.

In testimony whereof I have signed my name to this specification in the presence of 45 two subscribing witnesses.

SUEL J. SPAULDING.
